UNITED STATES PATENT OFFICE.

LORA BLANCHE LYON, OF DETROIT, MICHIGAN.

BUST-SUPPORTER.

No. 818,104.

Specification of Letters Patent.

Patented April 17, 1906.

Application filed July 14, 1905. Serial No. 269,600.

To all whom it may concern:

Be it known that I, LORA BLANCHE LYON, a citizen of the United States, residing at Detroit, county of Wayne, State of Michigan, have invented a certain new and useful Improvement in Bust-Supporters; and I declare the following to be a full, clear, and exact description of the invention, such as will enable others skilled in the art to which it pertains to make and use the same, reference being had to the accompanying drawings, which form a part of this specification,

This invention relates to bust-supporters.

It has for its object an improved cincture provided with pockets which are adapted to fit closely over the breasts of the wearer with narrow binding-bands both above and below the pockets, which are extended at the sides of a narrow band that passes around the back.

In the drawings, Figure 1 shows the cincture in position. Fig. 2 shows one-half of the cincture on a larger scale than that in Fig. 1.

The entire structure consists of a narrow belt or band A, provided with shaped pockets which are formed into shape by darts 2, 3, 4, and 5. At each edge both above and below the pockets are bound with a firm edging 6 at the upper side and a firm edging 7 on the under side, and these edging-strips extend around the back and form the edge-binding for a back-band that is stiffened with material 9 10, stitched firmly to the band and extending from the binding 12, which is an extension of the binding 6 to the binding 13, which is an extension of the binding 7. This stiffening material is preferably of canvas stitched to the body of the belt, with lines of stitching that run across from one band to the other and which are nearly vertical with respect to the proper position of the belt on the wearer. The upper line of binding 12 along the back is longer than the lower line 45 of binding 13, and when drawn around the wearer this upper line of binding is drawn closely against the under part of the shoulder-blades or just under the shoulder-blades, and the lower line of binding draws closely against

the person lower down on the taper of the 50 body toward the waist-line and holds the garment from slipping either up or down.

Fastening means, preferably tape 15 and 16, are secured to the ends of the cincture at the front edge-binding 11 in position to draw 55 along the edges of the binding 6 and 7 rather than over the pocket 8, and thus secures the belt to the person by drawing above and below the fullness of the breasts rather than across them, leaving the part of the garment 60 which covers the fullness of the breasts loose, while each of the bands 6 and 7, because of the intervening material which forms the pocket 8, is held in position.

Of course buttons might be substituted for 65 tapes; but the tapes are generally more satisfactory for this kind of garment than buttons.

When this garment is used by a person who is engaged in exercising, as when the person is engaged in outdoor sports or similar 70 occupations which require considerable muscular action, some more positive method of holding the support in position may be necessary, and this may be done by shoulder-straps 20, as are indicated in dotted lines in 75 Fig. 1.

What I claim is—

1. A bust-supporting cincture, having in combination bust-supporting pockets, a back-band connecting the same, a continuous 80 binding extending along the upper edge from end to end of the structure, a continuous binding extending along the lower edge from end to end thereof, independent fastening means whereby the top and bottom bindings 85 may be independently strained, substantially as described.

2. A bust-supporting cincture, having in combination bust-supporting pockets, a back-band, stiffening material extending across 90 the back-band from edge to edge thereof, a continuous binding extending along the upper edge of the entire cincture and a continuous binding extending along the lower edge of the entire cincture, and independent means 95 whereby the upper and lower edges may be independently strained, substantially as described.

3. A bust-supporting cincture, having in combination, a back connecting-piece, stiffening attachments transverse the said back-piece, bust-supporting pockets at the ends of said back-piece and connected thereby, a binding at the upper edge of the cincture continuous from end to end thereof, a binding at the lower edge of said cincture, the said binding at the upper edge being longer than the

binding at the lower edge, substantially as 10 described.

In testimony whereof I sign this specification in the presence of two witnesses.

LORA BLANCHE LYON.
